SERVING TRAY FOR AUTOMOBILES

Glen S. Wilson, Venice, Calif., assignor to
Alton Sims, Visalia, Calif.

Application August 20, 1956, Serial No. 42,669

Term of patent 14 years

(Cl. D14--6)

Fig. 1 is a front elevational view of a serving tray for automobiles embodying my new design;

Fig. 2 is a top plan view;

Fig. 3 is a side elevational view.

I claim:

The ornamental design for a serving tray for automobiles, substantially as shown.
